W. G. LEWIS

FOUNTAIN PEN HOLDER

Filed Feb. 26, 1927

Inventor
William Grey Lewis.

Patented June 21, 1927.

Des. 72,903

UNITED STATES PATENT OFFICE.

WILLIAM GREY LEWIS, OF CHICAGO, ILLINOIS.

DESIGN FOR A FOUNTAIN-PEN HOLDER.

Application filed February 26, 1927. Serial No. 20,904. Term of patent 14 years.

To all whom it may concern:

Be it known that I, WILLIAM GREY LEWIS, a citizen of the United States, residing at Chicago, in the county of Cook and State of Illinois, have invented a new, original, and ornamental Design for a Fountain-Pen Holder, of which the following is a specification, reference being had to the accompanying drawing, forming part thereof.

The figure is a perspective view of a fountain pen holder showing my new design.

I claim:

The ornamental design for a fountain pen holder substantially as shown.

WILLIAM GREY LEWIS.
